ELECTRICAL ALARM SWITCH

John Rowland Brown, Cleveland, Ohio, assignor
to The Reliance Gauge Column Company

Application June 4, 1949, Serial No. 97,237

3 Claims. (Cl. 200—138)

1

My invention relates to an alarm switch operated by the release of steam into the open from a steam boiler.

Many devices have been constructed wherein an electrical switch is operated when a steam whistle in a noisy factory blows to sound an alarm located remotely in a quiet office. These devices have always used pistons or parts extending from the switch into a steam chamber and required packing around the parts to prevent leaking of steam. My alarm switch has a bimetal strip on the outside of the steam chamber and responsive to steam exhausting from an opening in the chamber to operate the alarm switch and therefore does not have any pistons extending into the steam chamber and thus does not require packing. I have also found it advisable to extend the bimetal strip about the whistle to prevent wind blowing the steam away before it contacts the bimetal strip.

One of the objects of my invention is to construct an alarm switch which responds to steam blown into the open from an exhaust of a steam boiler or chamber housing.

Another object of my invention is to expose a bimetal strip to the steam exhausting or blowing into the open from a steam exhaust and have that bimetal strip operate an electrical switch.

Another object of my invention is to extend a bimetal strip at least partially around a steam whistle and in the path of exhausting steam and have that bimetal strip operate an electrical switch.

Another object of my invention is to provide an alarm operating in conjunction with a steam whistle wherein steam blowing from the steam whistle engages a bimetal strip which operates an alarm switch.

Other objects and a fuller understanding of the invention may be had by referring to the following description and claims, taken in conjunction with the accompanying drawings, in which:

Figure 1 is a side view of my alarm switch being used in conjunction with a steam whistle mounted on the side of a water column which is diagrammatically illustrated by the dash-dot lines.

Figure 2 is a front view of my alarm switch taken along line 2—2 of Figure 1; and

Figure 3 is a cross-sectional view of my alarm switch taken along line 3—3 of Figure 2.

In Figure 1 of my drawings, I illustrate the preferred embodiment and mounting of my alarm switch 10, wherein I use a steam whistle 11 as an exhaust for exhausting steam from a steam boiler or chamber, such as a water column 12. A shield

2

13 supports the switch 10 on one side thereof with the whistle 11 disposed on the other side thereof. This shield prevents steam, exhausting from the whistle 11 into the open or atmosphere, from coming in contact with the electrical switch 10. A temperature-responsive bimetal strip 14 extends at least partially into the path of blowing or exhausting of steam into the open and operates the electrical switch. When the bimetal strip 14 is extended about the whistle, wind will not blow the steam away from the whistle before it contacts the bimetal strip. The bimetal strip is always in the path of exhausting of the steam.

The switch 10 is an electrical switch which may be purchased on the market for opening and closing circuits, such for example as the alarm circuit of Figure 1. I have found it preferable to use a micro-switch having rubber bellows 15 supporting a switch-operating plunger 16. Movement of the plunger 16 operates the switch. In Figure 1 of my drawings, I have illustrated the end of a conduit 17 fastened to this switch 10 and through which wires 18 may be connected to a horn or other alarm 19 located at a distance from the switch. This signal device or alarm 19 may be positioned in a quiet office so that a worker who would not ordinarily be able to hear the steam whistle because of factory noise, would know when the water level in the boiler had reached a dangerous point.

The whistle 11 is carried by a nipple 20 threaded into the water column 12. This nipple has valves therein operable to release steam when the water level in the water column or boiler reaches a high or a low level. When the water level falls below a predetermined point, a low float 21 opens the whistle valve in the nipple 20 to release steam into the whistle, thus causing it to sound an alarm. Similarly, when the water rises above a predetermined point, a high float 22 is buoyed up, thus opening the whistle valve in the nipple 20 to blow the whistle. The structure of the nipple 20 and the valve therein is generally described in a prior Patent No. 1,322,598, issued November 25, 1919 to A. N. Miller et al. I do not herein describe the details of operation of this nipple 20 and the floats 21 and 22 to cause blowing of the whistle 11, since the operation is the same as that described in the above-mentioned patent. In understanding the operation of my invention, it should be kept in mind that blowing the whistle 11 exhausts steam from the boiler or water column 12 into the open or into the atmosphere.

The shield 13 is preferably formed from sheet metal and has a flange 24 extending outwardly therefrom on one end thereof and a support flange 25 extending outwardly from the other end thereof. This support flange 25 has an opening therein through which the threaded steam whistle support extends for engaging the nipple 20. When the steam whistle 11 is threadably tightened on to the nipple 20, the support flange 25 is rigidly disposed between the whistle 11 and the nipple 20. The shield 13 is thereby supported in parallel alignment with the whistle 11 and thus in parallel alignment with the path of exhausting or blowing of the steam into the open. When steam escapes or exhausts from a steam whistle it blows on the outside of the whistle and longitudinally thereof.

For purposes of the description, I describe the shield 13 as having a switch surface 26 on one side and a whistle surface 27 on the opposite side. The electrical switch 10 is fastened to the switch surface 26 and the whistle 11 is positioned next adjacent and close to the whistle surface 27. I have further provided the shield 13 with a slot 28 through which the bimetal strip 14 extends to operably engage the plunger 16 of the switch 10.

An angle member 29 having one side thereof, preferably but not necessarily, extending at right angles to the shield 13 and longitudinally of the whistle 11 is fastened to the whistle surface 27 to support the bimetal strip 14. It is understood that other suitable means may be used to fasten the bimetal strip 14 to the shield 13. However, I have found this angle member 29 to be the most practical. The slot 28 is disposed on one side of the shield 13 and the angle member 29 on the other side thereof. The whistle is close to the shield and between the angle member 29 and the slot 28.

The bimetal strip 13 is preferably secured to this angle member 29 by screws 30 and extends outwardly away from the whistle surface 27, around the whistle 11, and through the slot 28 to operably engage with the plunger 16 of the switch 10. The bimetal strip 14 is thus somewhat U-shaped with the mounting end of one leg secured to the shield 13 and with the free end of the other leg positioned to operate the switch 10. The surfaces of this bimetal strip 14 extend parallel to the path of blowing of steam into the open from the whistle 11 and are at least partially exposed for direct contact with the steam. Any pressures exerted by the steam in blowing into the open will be against the edge of the bimetal strip 14 or substantially transversely of the line of movement of the switch plunger 16 and will not cause the strip to operate the switch 10. In this manner, the switch 10 is operated primarily from the difference between the steam temperature and atmosphere temperature, since the bimetal strip 14 is responsive to a variation of temperature.

I have found it advisable to provide the free end 31 of the bimetal strip 14 which operates the switch 10 with an adjustment screw 32. This adjustment screw 32 is adjustably threadable through the free end 31 to regulate the amount of movement required by the free end 31 to operate the switch 10.

When the water level in the boiler reaches a high danger point or a low danger point, the steam whistle 11 blows. Steam is thereby ex-

hausted into the open in a path and contacts the surfaces of the bimetal strip 14 causing the bimetal strip 14 to respond to the difference in temperature. Upon responding to the difference in temperature, the bimetal strip 14 moves the plunger 16 of the switch 10 to operate the switch 10 and thereby either open or close an electrical signal circuit, such as the circuit illustrated in Fig. 1. It is thus seen that exhausting of steam from the boiler operates my alarm switch to signal a person located at a distance from the boiler.

Although the invention has been described in its preferred form with a certain degree of particularity, it is understood that the present disclosure of the preferred form has been made by way of example and that numerous changes in the details of construction and the combination and arrangement of parts may be resorted to without departing from the spirit and the scope of the invention as hereinafter claimed.

What is claimed is:

1. An alarm switch for steam boilers having an exhaust for blowing steam into the open, said alarm switch comprising, a shield mounted next adjacent and close to the said exhaust and parallel to the path of blowing of steam into the open, said shield having an opening therein, an electrical switch mounted on the side of the shield furthest from the exhaust, and a bimetal strip of modified U-shaped construction having one end thereof secured to the shield on the side closest to the said path and having the other end thereof extending through said opening and operably engageable with said switch, said bimetal strip having exposed surfaces parallel to and in the path of steam.

2. In an alarm system for steam boilers, a shield having a first surface and a second surface, an electrical switch supported next adjacent the first surface of said shield, a steam whistle next adjacent the second surface of said shield, and a bimetal strip of modified U-shaped construction extending close to and about said whistle, said bimetal strip having one end secured to the second surface of the shield and having the other end thereof operably engageable with said switch to operate the switch.

3. An alarm switch for steam boilers comprising, a steam whistle having an exhaust for blowing steam to atmosphere in a path encircling said whistle, an electric switch, a shield plate supported by said whistle and shieldingly carrying said switch, said shield plate having an opening therethrough, a bimetal element of modified U-shaped construction having one short leg and one long leg, and means mounting the short leg on said shield plate at a distance from said opening with said element extending close to and about said whistle and with the long leg extending through said opening in said shield into operative association with said switch.
